Attorney

UNITED STATES PATENT OFFICE.

RUDOLPH J. LINDHORST, OF CLEVELAND, OHIO.

RUG FASTENER.

Application filed April 11, 1927. Serial No. 182,978.

This invention relates to rug fasteners, and has for its object to provide an improved device by means of which the corners or edges of the rug may be fastened to a floor 5 without the use of tacks or the like.

In the present device this object is effected by means of a piece of double-faced adhesive tape which is attached to the under side of the rug and which may be stuck to the floor 10 to fasten the rug thereto. The piece of adhesive tape is covered or folded within a protective piece or backing of crinoline, which normally protects the tape before it is applied to the rug, and after being applied 15 the lower fold of the crinoline is opened to permit the tape to be applied to the floor. After one side of the tape has been used, and the rug is taken up, the device can be reversed to allow the opposite side of the tape 20 to be stuck to the floor. This doubles the duty of the fastener.

The invention is illustrated in the accompanying drawing in which Fig. 1 is a perspective view of the device, Fig. 2 is a sectional view illustrating the device applied 25 to a rug, Fig. 3 is a perspective of a section of the adhesive tape.

As many of the devices may be used as are necessary to suit the size of the rug, 30 usually one being applied to each corner, and each device consists essentially of a folded backing or protective piece indicated at 6, which may be crinoline or some cloth or material which will not stick to the adhesive tape, or which can easily be stripped therefrom. The tape is indicated at 7, inserted in the fold or between the leaves of 35 the backing. This tape is adhesive and double-faced, that is, having sticky material on

both sides, and has a hole 8 punched through 40 the same.

The device so constructed will be applied to the rug in the manner shown in Fig. 2. That is, by means of a penetrating fastener 9 inserted through the rug, the upper fold 45 of the crinoline backing, and the hole in the tape, and then bent down against the tape. The under fold of the backing, indicated in dotted lines in Fig. 2 at 6^a, is unfolded 50 against the under side of the rug, thereby exposing the under face of the adhesive tape and permitting the same to be stuck against the floor where it will retain the rug. While so used the upper surface of the tape will be 55 protected or covered by the backing. When the rug is taken up the device may be detached and reversed by removal of the fastener, the fold 6^a being then placed against the under side of the rug and the other fold being unfolded to uncover the unused face of 60 the tape and the fastener then inserted after which the exposed face of the tape can be stuck to the floor for the double use.

The device is capable of modification 65 within the scope of the following claims.

I claim:

1. A rug fastener comprises a piece of adhesive tape, and a folded cover thereon capable of being unfolded to expose the 70 face of the tape.

2. A rug fastener comprising a piece of double-faced adhesive tape, and a folded backing between the leaves of which the tape is enclosed, said backing being capable of 75 unfolding to expose either face of the tape.

In testimony whereof, I do affix my signature.

RUDOLPH J. LINDHORST.
